BENZIMIDAZOLONE DERIVATIVES

Fritz Hunziker, Bern, Switzerland, assignor to Dr. A. Wander, S.A., Bern, Switzerland, a corporation of Switzerland

No Drawing. Filed Jan. 29, 1965, Ser. No. 429,160
Claims priority, application Switzerland, Feb. 5, 1964, 1,333/64; Apr. 17, 1964, 5,017/64; July 30, 1964, 10,002/64

4 Claims. (Cl. 260—309.2)

This invention is generally concerned with certain derivatives of benzimidazolone (2-oxo-benzimidazoline), and more specifically with new benzimidazolone derivatives having a basic substituent on one nitrogen, of the formula:

10
15

and with acid addition salts thereof. In Formula I, R denotes a straight or branched alkylene residue with 2 to 4 carbon atoms; R₁ denotes a hydrogen atom, or together with R₂, an alkylene residue with 2 to 4 carbon atoms; R₂ denotes, besides, an alkyl residue with 1 to 3 carbon atoms, or together with R₃, an alkylene residue with 4 to 6 carbon atoms; R₃ denotes, besides, hydrogen or an alkyl residue with 1 to 3 carbon atoms; R₄ is in 5- or 6-position and denotes hydrogen, a halogen atom, or an alkyl residue containing 1 to 3 carbon atoms; and R₅ denotes hydrogen, a halogen atom, or an alkyl residue with 1 to 3 carbon atoms.

The said compounds are pharmacologically active substances whose pharmacological properties suggest that they may be useful especially as antidepressant and anticonvulsants. Whereas these two modes of action are found in similar measure in some representatives of the drug group, so in others one or other of the two modes of action is prominent. The antidepressant action predominates in the products substituted in 5-position and especially in 6-position, and the anticonvulsant action is especially prominent in the compounds substituted in the 1-phenyl residue, preferably in p-position. Halogen atoms, and particularly chlorine, are preferred as substituents R₄ and R₅. The basic side-chain in 3-position is preferably a γ -dimethylaminopropyl, γ -diethylaminopropyl, or γ -pyrrolidin-1'-ylpropyl residue. Examples of compounds with special anticonvulsant activity are 1-p-chlorophenyl-3- γ -diethylaminopropyl-benzimidazolone, 1-p-chlorophenyl-3- γ -pyrrolidin-1'-yl-propyl-benzimidazolone and their acid addition salts, and of those having special antidepressant activity are 1-phenyl-3- γ -dimethylaminopropyl-6-chlorobenzimidazolone and its acid addition salts.

The new compounds of this invention can be administered in the form of pharmaceutical preparations containing, besides the active substance, organic or inorganic solid or liquid carriers suitable for enteral or parenteral administration. The pharmaceutical preparations may be, for instance, in the form of tablets, dragees, or solutions for injection, one dosage unit containing from 40 to 100 mg. of active substance, depending on its nature, on the

2

route of administration and on the physician's prescription, the effective daily dose amounting from 100 to 1000 mg. of active substance.

Compounds of Formula I are obtained by introducing 5 into benzimidazoles of the formula:

10
15

wherein R₄ and R₅ have the above-mentioned meaning, a basic residue of the formula $—R(R_1)—NR_2R_3$, wherein R, R₁, R₂ and R₃ have the said meaning. The basic residue is introduced by treating the compound of Formula II, which is suitably dissolved in an inert solvent such as benzene, dioxan, dimethylformamide, dimethylsulphoxide or mixtures thereof, with the ester of an alcohol of the formula:

20
25
30
35
40
45

wherein R, R₁, R₂ and R₃ have the meaning indicated earlier, preferably at increased temperature and if necessary after prior or during simultaneous exposure to the action of a condensing agent. Suitable esters are those of inorganic and organic acids such as hydrohalic, sulphuric, sulphonic, or carbonic acid. If carbonic acid esters are used the condensing agent can in general be dispensed with, but it is usually necessary in case of the other esters just mentioned. Suitable condensing agents are especially alkaline metals, their hydrides and amides, as well as other compounds of alkaline metals, for example sodium alcoholate, sodium amide, sodium hydride, phenylsodium, alkyl lithium, or potassium-t-butoxide. The benzimidazolones of Formula I used in this reaction are obtained, for example, by reacting appropriately substituted phenylenediamines of the formula:

50
55

wherein R₄ and R₅ have the meaning mentioned earlier, with a reactive carbonic acid derivative such as phosgene.

In so far as R₁ in Formula I denotes hydrogen the desired benzimidazolones are also obtained by reacting esters of alcohols having the formula:

60
65
70

(V)

wherein R, R₄ and R₅ have the meaning indicated earlier, e.g. hydrohalic, sulphuric, or sulphonic acid esters, with an amine of the formula HNR₂R₃, wherein R₂ and R₃ have the above-mentioned meaning. Esters of alcohols of Formula V are in turn obtained, for example, by reacting compounds of Formula II with a—preferably mixed—diester of an alkyleneglycol containing 2 to 4 carbon atoms, e.g. with an alkylene chlorobromide, if necessary after prior or during simultaneous exposure to the action of a condensing agent. On the other hand one can also first treat compounds of Formula II with an alkylene oxide or alkylene halohydrin containing 2 to 4 carbon atoms or with an alkylene-halohydrin tetrahydropyranyl ether of the formula:

and then—in the latter case, after splitting off the protective group—form the desired ester, for example, by reacting with a thionylhalide or a hydrohalic acid.

Products of Formula I, wherein R₁ is hydrogen, are also formed by introducing residues R₂ and R₃ into primary amines having the formula:

wherein R, R₄ and R₅ have the meaning indicated earlier, for example by reacting the latter with esters, especially hydrohalic acid esters, of alcohols of the formula HO—R₂ or HO—R₂—R₃—OH, or by reacting the primary amines with corresponding aldehydes in accordance with the method of reductive alkylation, using hydrogen in the presence of a catalyst or using a reducing agent such as formic acid. The starting materials of Formula VII are in turn obtained, for example, by reacting esters of the alcohols of Formula V with ammonia or by reduction of suitable nitriles.

Compounds of Formula I are also obtained by reacting substituted o-phenylenediamine derivatives of the formula:

wherein R, R₁, R₂, R₃, R₄ and R₅ have the meaning indicated earlier, preferably in the presence of an inert solvent, with a reactive derivative of carbonic acid, e.g. phosgene, diethylcarbonate, urea and the like, if required after prior or during simultaneous exposure to the action of a condensing agent. Suitable solvents and condensing agents are the substances mentioned earlier for this purpose. The starting substances of Formula VIII are obtained, for example, by condensation of the ester of an alcohol having Formula III with a phenylenediamine

derivative of Formula IV, if necessary after, prior or during simultaneous exposure to the action of a condensing agent for the above-mentioned kind, if required with intermediate acylation of at least the primary amino group.

Lastly, compounds of Formula I, wherein R₄ and/or R₅ denote halogen, are obtained by replacing other substituents having the same position by the desired halogen atom, for example by diazotizing and subsequent Sandmeyer's reaction of corresponding amino compounds, which in turn may be prepared by reduction of corresponding nitro compounds.

The basic-substituted benzimidazolones of Formula I synthesized according to one of the processes described earlier can be obtained and used, not only as free bases but also in the form of their addition salts with suitable acids, such as hydrohalic acids, sulphuric, nitric, phosphoric, acetic, oxalic, malonic, succinic, maleic, or toluene-sulphonic acid.

EXAMPLE 1

7.5 g. of 1-phenyl-benzimidazolone (1-phenyl-2-oxo-benzimidazoline) in 50 ml. of absolute dioxan are boiled with 1.68 gm. of pulverized sodium amide for 1 hour under reflux. After adding 5.4 gm. of β -dimethylaminoethylchloride in 30 ml. of benzene the whole is heated at boiling temperature for another 16 hours. After evaporating the reaction mixture to dryness in *vacuo* the residue is distributed between benzene and water. The basic fractions are removed from the lipoid phase by exhaustive extraction with dilute acetic acid. The base precipitated from the combined extracts with concentrated ammonia solution is taken up in benzene. The benzene solution is washed several times with water, dried over sodium sulphate and evaporated to dryness. After clarification in benzene solution on alumina there are obtained from benzene/petroleum ether and acetone/petroleum ether 8.8 gm. (88% of the theory) of 1-phenyl-3- β -dimethylaminoethyl-benzimidazolone of melting point 116–117° C.

EXAMPLE 2

6.1 gm. of 1-phenyl-6-chloro-benzimidazolone are boiled with potassium-t-butoxide (from 1.0 gm. of potassium) in 40 ml. of t-butanol for 10 minutes under reflux. After evaporating the reaction mixture to dryness in *vacuo* the potassium compound is mixed with 40 ml. of dimethylformamide and heated with 4.8 gm. of freshly distilled 1-methyl-3-chloromethyl-piperidine for 18 hours at 50° C.

On proceeding as described in Example 1 3.4 gm. of a crystalline neutral substance are obtained consisting mostly of 1-phenyl-6-chloro-benzimidazolone (starting material). As the base there are obtained 2.7 gm. of 1-phenyl-3-(1'-methylpiperidyl-3')methyl-6-chloro-benzimidazolone in the form of colourless needles of melting point 112–114° C. (from ether/petroleum ether), which, taking into consideration 2.8 gm. of pure starting material recovered, corresponds to a yield of 58% of the theoretical.

EXAMPLE 3

7.3 gm. of 1-phenyl-benzimidazolone in 40 ml. of absolute dioxan are boiled with potassium-t-butoxide (from 1.2 gm. of potassium) in 30 ml. t-butanol for 1 hour under reflux. Upon addition of 5.7 gm. of trimethylene chlorobromide, refluxing is continued for another 7 hours. The reaction mixture is concentrated and the residue is distributed between ether and water. A small amount of substance insoluble in either of both phases is separated by filtration. The ethereal solution is washed with water and evaporated to dryness in *vacuo*, yielding 6.4 gm. of a brown resin. The latter is boiled with 5.0 gm. of dimethylamine in 20 ml. of dioxan for 18 hours in a sealed tube. By working up the reaction mixture in a usual manner, 4.9 gm. of 1-phenyl-3- γ -dimethylamino-

propyl-benzimidazolone of boiling point 163° C./0.03 mm. Hg are obtained.

EXAMPLE 4

6.3 gm. of 1-phenyl-3- γ -aminopropyl-6-chloro-benzimidazolone are heated with 10 ml. of 90% formic acid and 5 ml. of 35% formaldehyde for 15 hours at 100° C. Upon addition of 2 ml. of 38% hydrochloric acid the reaction mixture is evaporated in vacuo and the residue is dried. Recrystallizing of the residue from methanol/acetone/ether with use of charcoal yields 6.1 gm. of 1-phenyl - 3 - γ - dimethylaminopropyl - 6 - chloro - benzimidazolone hydrochloride of melting point 180-182° C.

EXAMPLE 5

12.3 gm. of N_1 -phenyl- N_2 -(β -dimethylamino)ethyl-o-phenylenediamine are heated with 4.0 gm. of urea for 15 hours at 200° C., while passing gaseous nitrogen over the reaction mixture. From the basic fractions, separated as described in Example 1, 8.4 gm. of 1-phenyl-3- β -dimethylaminopropyl-benzimidazolone are obtained which is identical with the product of Example 1.

EXAMPLE 6

8.7 gm. of 1-p-aminophenyl-3- γ -pyrrolidin-1'-yl-propyl-benzimidazolone are dissolved in 100 ml. of 1-n hydro-

chloric acid and diazotized at 0° C. with a solution of 1.9 gm. of sodium nitrite in 10 ml. of water. The diazonium solution is added within 10 minutes to an aqueous solution of cuprous chloride (prepared from 5.3 gm. of copper sulphate and 5.3 gm. of sodium chloride in 25 ml. of water by introducing gaseous sulphur dioxide) stirred at 80° C., this temperature being maintained for 30 minutes after the evolution of gas had ceased. The reaction mixture is allowed to cool and then alkalized by addition of soda lye. The basic precipitate is dissolved in ether. The ethereal phase is washed with diluted soda lye and with water and worked up in a usual manner. The residue is dissolved in petroleum ether, purified by contact with aluminium oxide, and crystallized from cold petroleum ether. By this procedure 5.6 gm. of 1-p-chlorophenyl-3- γ -pyrrolidin - 1' - yl - propyl - benzimidazolone of melting point 54-56° C. are obtained.

By means of the same procedure as in Examples 1 to 6 there are also obtained, for example, the products mentioned in the following table. In the table R , R_1 , R_2 , R_3 , R_4 and R_5 are the corresponding groups in Formula I, with the meaning stated earlier. In the column on the right are given in brackets the solvents or solvent mixtures from which crystallization was effected: here ac means acetone, e ether, me methanol, pe petroleum ether and pn pentan.

TABLE

Example	$ \begin{array}{c} R_1 \quad R_2 \\ \quad \diagdown \\ -R-N \quad R_3 \\ \quad \diagup \\ \end{array} $	R_4	R_5	Melting point (M.P.) or Boiling point (B.P.)

Production of tablets.—For the manufacture of tablets, the products of this invention can be mixed with lactose and granulated with water, 0.5% sodium alginate or 1% gelatine solution. The dried granulate is compressed into tablets in the presence of about 5% of talcum, 5% of corn starch and 0.1% of magnesium stearate. In this way, there are obtained, e.g. tablets of the following composition:

Mg.	
1 - phenyl - 3 - γ - dimethylaminopropyl - 6 - chloro-	35
benzimidazolone hydrochloride	40
Lactose	60
Corn starch	5
Talcum	2
Magnesium stearate	0.1

These 107 mg. tablets can be administered orally in a dosage of 3 to 15 tablets per day in the treatment of patients suffering from states of mental depression.

We claim:

1. A compound selected from the class consisting of A: benzimidazolone derivatives of the formula:

wherein R denotes alkylene with from 2 to 4 carbon atoms; R₁ is a member of the group consisting of hydrogen and, taken together with R₂, alkylene with from 2 to 4 carbon atoms; R₂ is a member of the group consisting of alkyl with from 1 to 3 carbon atoms, together with R₁, alkylene with from 2 to 4 carbon atoms, and, together with R₃, alkylene with from 4 to 6 carbon atoms; R₃ is a member of the group consisting of hydrogen, alkyl with from 1 to 3 carbon atoms, and, together with R₂, alkylene with from 4 to 6 carbon atoms; R₄ is in 5- or 6-position and denotes a member of the group consisting of hydrogen, halogen, and alkyl with from 1 to 3 carbon atoms; and R₅ is a member of the group consisting of hydrogen, halogen, and alkyl having from 1 to 3 carbon atoms; and B: pharmaceutically acceptable acid addition salts of A.

2. 1 - p - chlorophenyl - 3 - γ - diethylaminopropyl-benzimidazolone.

3. 1 - p - chlorophenyl - 3 - γ - pyrrolidin - 1' - yl - propyl-benzimidazolone.

4. 1 - phenyl - 3 - γ - dimethylaminopropyl - 6 - chloro-benzimidazolone.
